UNITED STATES PATENT OFFICE.

HENRY D. SMELSER, OF WEST PLAINS, MISSOURI.

DEVICE FOR CONCENTRATING THE RAYS OF THE SUN.

1,111,289.

Specification of Letters Patent. Patented Sept. 22, 1914.

Application filed April 18, 1914. Serial No. 332,934.

To all whom it may concern:

Be it known that I, HENRY D. SMELSER, a citizen of the United States, residing at West Plains, in the county of Howell and State of Missouri, have invented certain new and useful Improvements in Devices for Concentrating the Rays of the Sun; and I do declare the following to be a full, clear, and exact description of the invention, such as will enable others skilled in the art to which it appertains to make and use the same.

My invention relates to improvements in devices for reflecting and concentrating the rays projected from the sun and has for its primary object to provide a plurality of reflectors so positioned as to reflect and concentrate the rays of sun to a single point and also having means whereby the direction in which said rays are reflected, may be varied.

In carrying out the above end, I provide a number of reflectors which are mounted for both vertical and lateral swinging movement, means for simultaneously adjusting all of said reflectors vertically, and independent means for simultaneously adjusting said reflectors in a lateral plane.

A secondary object of the invention resides in the construction and arrangement of the operating means.

Still another object of the invention is to provide a device which will be simple, strong and durable, and which will effectually perform the function for which it is designed.

With the above objects in view, the invention resides in certain novel features of construction and combination herein described and claimed and shown in the drawings wherein:

Figure 1 is a plan view of my invention showing the manner in which the reflectors may be adjusted; Fig. 2 is a vertical transverse section taken on the line 2—2 of Fig. 1; Fig. 3 is a central vertical longitudinal section through the entire device; Fig. 4 is an elevation of one of the reflectors supporting frames and its reflector, showing more particularly the construction of these parts; Fig. 5 is a vertical section on the line 5—5 of Fig. 4; Fig. 6 is a horizontal section on the line 6—6 of Fig. 4; Fig. 7 is a detail vertical section on the line 7—7 of Fig. 5; and

Fig. 8 is a diagrammatic top plan view 55 showing the manner in which the reflectors concentrate the rays of light to a single point, the operating means for said reflectors being eliminated for the sake of clearness.

In the accompanying drawings, I have 60 shown my invention as comprising a base 1, a number of upright supporting frames 2, rising rigidly therefrom, a plurality of reflector supporting frames 3 mounted for horizontal swinging movement in the frames 65 2, a number of reflectors 4 mounted within said frames 3 for vertical swinging movement, means for simultaneously effecting the horizontal swinging movement of said reflector supporting frames, and independent 70 means for simultaneously effecting the vertical swinging movement of said reflectors.

The frames 2 may be of any suitable construction and are here shown as comprising 75 upper and lower transverse bars 5 and 6, respectively, which are disposed between upright standards 7, the latter constituting the sides of the frames. As clearly shown in Figs. 1 and 3, the frames 2 are spaced longitudinally upon the base 1, the distance between said frames being sufficient to allow the rays, reflected from the reflectors 4, to pass upwardly over the transverse bars 5. In the present illustration, I have shown but 80 three of the frames 2 and three reflectors mounted in each frame. It will be evident, however, that I need not be limited to the number of frames or the number of reflectors employed.

The frames 3 are preferably of rectangular formation and are spaced equi-distantly within the frames 2, said frames 3 being mounted upon vertical pivots 8 which project from the upper and lower cross bars of 95 said frames 3 through the upper and lower cross bars of the frames 2.

As clearly shown in the various figures of the drawings, the reflectors 4 are pivoted to swing vertically within the frames 3, transversely extending pivot studs 9, projecting rigidly from the frames of the reflectors and journaled into the upright bars of the frames 3, being preferably employed for this purpose.

For the purpose of turning all of the frames 3 simultaneously upon their pivots 8, I provide a revolvably mounted drum 10,

which is preferably positioned upon one of the longitudinal sides of the base 1 and extends transversely of said base. Wound a plurality of times around the drum 10 and having its free ends projecting longitudinally therefrom and passing around guide pulleys 11, is a main operating cable 12, said cable having supplemental cables 13 at suitable intervals, said cables 13 extending longitudinally of the base 1 and being secured by means of clamps 14 to certain of the upright bars of the mirror supporting frames 3. As clearly shown in Fig. 1, a pulley 11 is positioned to each end of a longitudinal row of reflectors, said pulleys being supported in any suitable manner as by upstanding bars 15 which extend transversely across the base 1. The cable 12 extends through the pulleys 11 to the opposite side of the machine and here has its free ends united as shown at 16. By this arrangement of parts, it will be seen that when the drum 10 is rotated by means of a shaft 17 or other suitable means, the cable 12 to one side of the drum, will be wound thereon, while the portion of the cable to the opposite side of the drum, will be allowed to move outwardly, this movement on the part of the cable 12 actuating the cables 13 in such a manner as to simultaneously rock all of the frames 3 around their pivots 8. Similar operating means is provided for the purpose of swinging the reflectors 4 in vertical planes, said operating means comprising a drum 10', a main operating cable 12', passing around the pulleys 11' and having a number of longitudinal branch cables 13' secured thereto at suitable intervals, said cables 13' being secured to the lower edges of the reflectors 4 by means of clamps 14'. Thus, it will be seen that when the shaft of the drum 10' is rotated, the reflectors 4 will be rocked simultaneously in vertical planes.

By the provision of the clamps 14 and 14', the angular relation of the frames 3 with the cables 13 and that of the reflectors 4 with the cables 13', may be varied at will, this provision being made in order that said reflectors may be properly positioned for causing the light reflected therefrom, to be concentrated at a single point (see Fig. 8). In this figure, the rays of light, coming from the sun or other suitable source, are considered as falling directly in vertical lines, or in other words, at right angles to the upper face of the base 1. If it becomes necessary to shift the point at which the rays of light are concentrated, this may be easily done through the action of the drums 10 and 10', as before described.

The motive power, for driving the drums 10 and 10' may be in any suitable form, but I prefer to employ an electric motor (not shown), and gearing (not shown) between

said motor and said shafts, said gearing being so arranged as to cause the shafts of the drums to travel at slower speeds than the shaft of the motor.

From the foregoing description, taken in connection with the accompanying drawings, it will be seen that I have produced a comparatively simple, yet highly efficient machine which will readily perform the function for which it is designed.

The rays, reflected from the various reflectors 4, will, of course, generate an extremely high temperature at the point to which they are concentrated. The heat thus generated, may be transformed into motive power or otherwise employed, its disposition forming no part of the present invention.

I have described my invention with considerable minuteness as to details, but I do not wish to be limited thereto other than as set forth in the appended claims.

Having thus described my invention, what I claim as new and desire to secure by Letters Patent is:

1. A solar device comprising a base, a number of longitudinal rows of reflector supporting frames pivotally mounted upon said base upon vertical axes, a number of reflectors pivotally supported in said frames upon horizontal axes, a pair of guides at each end of each of said rows of frames, a pair of drums spaced laterally from one of the outermost of said rows, endless cables completely encircling said rows of frames, said cables being passed through said guides and wound a number of times around said drums, branch cables extending longitudinally of said longitudinal rows of frames and secured to the lower ends of said reflectors, said branch cables being engaged with certain of said guides and secured to one of said endless cables and other branch cables extending longitudinally of the rows of frames and secured to the sides of said frames, the ends of said last mentioned branch cables being engaged with certain of the remaining guides and secured to the other endless cable.

2. A solar device comprising a base, a number of longitudinal rows of reflector supporting frames pivotally supported on said base upon vertical axes, clamps on one side of each of said frames, reflectors pivotally supported in said frames upon horizontal pivots, clamps on one end of each of said reflectors, a pair of guides at each end of each of said rows of frames, a pair of drums revolubly supported adjacent one of the outermost of said rows, endless cables completely encircling said rows of frames and engaged with said guides, said cables being wound a number of times around said drums, branch cables extending longitudinally of said rows and secured within the

clamps on said frames, said branch cables being engaged with certain of said guides, and other branch cables extending longitudinally of said rows and secured in the clamps on said reflectors said last mentioned branch cables being engaged with certain of the remaining guides.

In testimony whereof I have hereunto set my hand in presence of two subscribing witnesses.

HENRY D. SMELSER.
